UNITED STATES PATENT OFFICE.

GEORGE HUNT, OF ELLENVILLE, NEW YORK.

POCKET-KNIFE.

SPECIFICATION forming part of Letters Patent No. 303,855, dated August 19, 1884.

Application filed November 3, 1883. (Model.)

To all whom it may concern:
Be it known that I, GEORGE HUNT, of El-
lenville, town of Wawarsing, county of Ulster,
and State of New York, have invented a new
5 and useful Combined Blade-Opener and Nail-
Spur Attachment to Pocket-Knives; and I do
hereby declare the following to be a full, clear,
and exact description of the invention, such
as will enable others skilled in the art to which
10 it appertains to make and use the same.

My invention relates to pocket-knives; and
it has for its object to combine with the blade
or blades of an ordinary knife a spur or pro-
jection which serves as a finger-nail cleaner,
15 and to provide the knife-blade with a suit-
ably-arranged perforation or opening, whereby
the said blade may be readily opened by
means of a pin or like object, thus obviating
the inconvenience and annoyance experi-
20 enced with the ordinary blade when the spring
is rather stiff or has become rusted.

With these ends in view the invention con-
sists in the improved construction of knife-
blade hereinafter fully described, and pointed
25 out in the claim.

In the drawing the single figure represents
a side elevation of an ordinary knife, the blades
of which are constructed in accordance with
my invention.

A represents a knife-handle of the ordi- 30
nary construction, having blades D attached
thereto in a suitable or well-known manner.
These blades D are provided upon their upper
edges with upwardly-extending spurs or pro- 35
jections B C, which are designed to subserve
the double purpose of a finger-nail cleaner
and convenient means by which to open the
blade. Upon the blades D are provided holes
or openings x at any desired point, though
40 preferably near the upper edge and near the
end of the blade. By providing a knife-blade
with these perforations it will be seen that
when the blade becomes rusted or the easy
opening otherwise impaired a pin or like ob- 45
ject may be passed through said perforation
and the blade easily opened.

I claim—

A knife having one or more of its blades
formed with an obliquely-projecting spur, said
blade or blades being also provided with a per- 50
foration near the upper edge thereof, substan-
tially as set forth.

GEORGE HUNT.
